UNITED STATES PATENT OFFICE.

JOHN W. WARD, OF LATROBE, PENNSYLVANIA, ASSIGNOR TO THE PITTSBURG HIGH VOLTAGE INSULATOR CO., OF DERRY, PENNSYLVANIA.

INSULATOR-SUPPORT FOR TOWERS.

1,237,843.

Specification of Letters Patent. Patented Aug. 21, 1917.

Application filed December 24, 1915. Serial No. 68,489.

To all whom it may concern:

Be it known that I, JOHN W. WARD, a citizen of the United States, residing at Latrobe, in the county of Westmoreland and State of Pennsylvania, have invented certain new and useful Improvements in Insulator-Supports for Towers, of which the following is a specification.

This invention relates to an improvement 10 in insulator supports for towers, and the object is to provide an insulated base for support and insulation of electric conductors, and especially for use in connection with currents of high voltage, the invention consisting of a series of plates or disks built in 15 combination to form an insulated base for support of heavy towers, and which are constructed of solid material for compressive strength to sustain heavy loads.

20 The invention consists of certain novel features of construction and combinations of parts which will be hereinafter described and pointed out in the claims.

In the accompanying drawings:—

25 Figure 1 is a longitudinal vertical sectional view through the invention; and Fig. 2 is an enlarged detail sectional view. A, represents an iron base, which is provided with a recess 1, and mounted on the 30 base is an insulating plate 2, preferably constructed of porcelain, which has a recess 3 formed in its upper and lower sides. The recess 3 on one side of the plate registers with the recess 1 of the iron base A, and received in the recesses 1 and 3 is an insulating disk 4, which may be made of porcelain. The base, disk and plate are all connected together by cement.

35 All of the plates are preferably constructed alike, and the disk 4 is interposed between the adjacent plates and received in the recesses 3 thereof, so that the plates and disk can be connected together by the introduction of cement therebetween. As shown 40 in the drawings, the outer surface or periphery of the disk 4 is corrugated, and the inner surface of the plates or wall of the recesses 3 is corrugated, for forming a rough surface which will form a surface for the cement to 45 adhere to for forming a secure connection between the parts.

It is essential in connecting the several parts together that there are no breaks or

air spaces, and to overcome this, a coating of cement is applied beneath each disk 4, so 55 that it will adhere to the bottom of the recess 3 of the plate. Such a connection is formed on both sides of the disk. Although the coating may be in the form of a thin film, it will take up the uneven surfaces formed 60 on the disks and plates caused by a distortion in the firing operation.

In making the tests, it has been found that to obtain the highest efficiency that all of the parts must be securely connected together by introducing a coating of cement which will cover the entire engaging surfaces of the members, so that no air spaces or breaks may be found. With an insulator constructed in the manner set forth, 70 wherein the parts are coated with cement, that is their joining surfaces, which were nine inches square, it stood over a million pounds test without any difficulty. Yet, with an insulator which was not coated with 75 the cement where the several members join, the insulator would only stand a test of from two hundred and fifty thousand to three hundred thousand pounds pressure.

80 It is also essential that the surfaces of the metal base A, and the metal cap 5 which is mounted upon the uppermost plate 1, should have a like surface, that is, the surfaces should be parallel. They should be machined so that they are absolutely parallel so that 85 when the strain is placed upon the insulation, the strain will be distributed equally throughout the insulated block, and not at some fractional portion of the block. Naturally if the strain is not equally distributed, 90 the block will be unable to withstand the load.

95 The cap 5 is provided with a recess 6 in which the uppermost disk 4 is received, and cement is placed between the disk and cap so that a positive seal is formed between the two.

100 The various sections are all constructed solid and nest into each other, they being provided with either smooth or rough surfaces, and are all fastened to each other with cement.

105 The outside surfaces are smooth to prevent dirt or any other foreign substance from adhering to the surface, and can be cleansed readily by rain or water. The pet-

ticoat effect is to increase the creepage distance under normal conditions when it is raining or storming.

I claim:

- 5 1. An insulating support for towers for high-tension conductors comprising a plurality of solid insulating members provided with recesses upon both sides, flat disks substantially of the same thickness as the distance 10 between the recesses, and received therein for connecting the plates together, a base and cap provided with recesses adapted to be received upon the two end disks, and means for connecting the several parts together.
- 15 2. An insulating support for towers for high tension conductors comprising a plu-

rality of solid insulating members provided with recesses upon both sides, the combined depths of which equal the thickness of the intervening spaces, flat disks substantially 20 of the same thickness as the spaces between the recesses, received within the recesses, thereby forming a plurality of supporting surfaces of equal strength, a base and cap provided with recesses and adapted to be received upon the two end disks, and means for connecting the several parts together. 25

In testimony whereof I affix my signature, in the presence of two witnesses.

JOHN W. WARD.

Witnesses:

ANNA E. WATSON,
W. ARTHUR EMRICK.
